UNITED STATES PATENT OFFICE.

ENOCH P. STEVENS, OF CHICAGO, ILLINOIS; MARY ANN STEVENS EXECUTRIX OF
SAID ENOCH P. STEVENS, DECEASED.

HANGER FOR ARCH BRICKS.

Application filed January 19, 1922. Serial No. 530,277.

To all whom it may concern:

Be it known that I, ENOCH P. STEVENS, a citizen of the United States, residing at Chicago, in the county of Cook and State 5 of Illinois, have invented certain new and useful Improvements in Hangers for Arch Bricks, of which the following is a specification.

This invention relates to furnace arches of 10 that type in which arch-forming brick are supported by clips suspended from a beam or other overhead structure and fashioned to enter into supporting engagement with reentrant portions of the bricks.

15 One object of the invention is to provide a construction of clip that will grip the brick indirectly through the medium of an interposed member or members (hereinafter referred to as "inserts") and therefore without 20 direct embrace or impingement against the brick by the clip, which, in constructions heretofore employed has frequently caused spalling of the gripped portion of the brick.

Another object is to adapt such a clip to 25 sustain a series of bricks of materially greater aggregate dimension than that of the clip by making the inserts sufficiently rigid and of sufficient longitudinal dimension to adapt them to develop bridging suspension of the 30 group of bricks lying between two clips, or, sustain, by cantilever principle, bricks lying on either side of and beyond the immediate embrace of a clip.

A further object is to provide details of 35 construction of the parts which enter into the organization of elements employed whereby the before-mentioned objects will be realized with economy and efficiency.

In the accompanying drawings in which 40 the preferred embodiment of the invention is illustrated—

Figure 1 is an elevational view showing an arch sprung between two abutments and having its constituent bricks suspended by 45 hangers embodying the several features of the present invention.

Figure 2 is a detail view showing a brick in elevation and the supporting hanger in vertical transverse section.

50 Figure 3 is an end view and Figure 4 a side elevation of one of the inserts employed; and

Figure 5 is a top plan view of a hanger with its suspending rod in section.

55 1 represents bricks composing an arch

sprung between abutments 2 such, for instance, as furnace walls, and 3 represents an overhead beam adapted to support the arch at suitable intervals through the medium of hangers comprising rods 4 and brick-engaging clips 5. To adapt the bricks 1 to be so supported, it is common to make them with a neck 6 fashioned to develop shoulders, undercuts, or reentrant portions which may readily be gripped by the clips. 60

According to the present invention, the clip 5 comprises a suspending head 7 formed with a recess 8 that receives the eye or hook 9 of the suspending rod 4, and a through bolt 10 which secures the hook therein with freedom of angular motion relatively thereto; also brick-embracing jaws 11. But the jaws 11 do not come into direct bearing upon the neck 6 of the brick 1; instead they sustain the brick indirectly through the medium of inserts 12 which are fashioned to conform to the surfaces of the brick and jaws between which they lie. Inserts 12 are elongated in the longitudinal direction of the arch so that in addition to transmitting support from the clip 5 to a brick or bricks immediately underlying the clip, said inserts extend beneath the shoulders of a plurality of bricks on either side of the clip, or preferably bridge the space from one clip to another so as to support the intermediate bricks, as shown in Figure 1, each clip bridging the opposed ends of two pairs of clips. 70

Inserts 12, being of approximately concave or angular section, as shown in Figure 3, develop substantial rigidity both vertically and horizontally and thus become particularly adapted to keep the bricks in alignment with the arch. Moreover, these inserts partake of the curvature of the arch and have one flange or leg of the substantially angular or concave section lying approximately in the plane of arching, thereby stiffening the vertical support, and the other flange or leg of the section presented in a direction which is made up largely of a horizontal component which not only develops the support beneath the shoulder of the brick but greatly stiffens the insert against horizontal distortion under the heat of the 75 furnace. 100

The clip 5 may be made separable into two parts, as, for instance, by dividing its head 7 on the line 7^a, and uniting said parts through means of the bolt 10. 110

With the construction as shown, not only is the arch efficiently sustained by means of cheap and durable construction, but any section of an arch is made readily removable, 5 since it is merely necessary to shift a clip in the longitudinal direction of the arch a distance sufficient to release one end of a pair of inserts 12, which normally lie within the clip, when the inserts can be removed 10 and any one or more of the bricks sustained thereby can be replaced, after which the inserts are replaced and the clip is restored to its position to embrace the adjacent ends of the inserts, whereupon the arch will be 15 ready for further use.

I claim:

1. In an arch construction, a clip adapted to sustain bricks through the medium of reentrant portions of the bricks, and an insert 20 interposed between a clip and a brick and extending into sustaining relation to bricks lying beyond the clip.
2. In arch constructions, embracing clips 25 fashioned to sustain a brick through engagement with a reentrant portion of the brick, and inserts adapted to be interposed between said clips and said reentrant portion, conforming in section to the clip and to 30 the reentrant portion of the brick, and having longitudinal dimensions which adapt them to extend beyond the clip into reentrant portions of adjacent bricks and thereby sustain the latter in the arch.
3. In an arch construction, the combination 35 of bricks having reentrant portions through which they are sustained, inserts conforming to the reentrant portions of a series of bricks and thereby adapted to sustain said bricks in alignment, and clips 40 bracing and supporting said inserts.
4. In an arch construction, a series of 45 bricks having sustaining shoulders, a plu-

rality of inserts arranged end to end beneath said shoulders, and clips engaging and sustaining adjacent ends of the inserts, 45 thereby adapting the inserts to sustain bricks lying between the clips.

5. In a furnace arch construction, a clip, and an insert through which the clip is 50 adapted to support the bricks; said insert partaking of the curvature of the arch and extending beyond the clip in supporting relation to bricks adjacent thereto.

6. In a furnace arch construction, a clip, and an insert through which the clip is 55 adapted to support the bricks; said insert partaking of the curvature of the arch and extending beyond the clip in supporting relation to bricks adjacent thereto; and said 60 insert being of approximately angular section.

7. In a furnace arch construction, a clip, and an insert through which the clip is 65 adapted to support the bricks; said insert partaking of the curvature of the arch and extending beyond the clip in supporting 70 relation to bricks adjacent thereto; and said insert being of approximately angular section with one leg of its section presented approximately in the plane of arching.

8. In a furnace arch construction, a clip, and an insert through which the clip is 75 adapted to support the bricks; said insert partaking of the curvature of the arch and extending beyond the clip in supporting 80 relation to bricks adjacent thereto; and said insert being of approximately angular section with one leg of its section presented approximately in the plane of arching, and with the other leg of said section approxi- 85 mately horizontal.

Signed at Chicago, Illinois, this 6th day of January, 1922.

ENOCH P. STEVENS.
